UNITED STATES PATENT OFFICE.

THOMAS W. MILLER, OF AKRON, OHIO.

PROCESS OF FORMING HOLLOW SEAMLESS RUBBER ARTICLES.

SPECIFICATION forming part of Letters Patent No. 687,249, dated November 26, 1901.

Application filed August 10, 1901. Serial No. 71,552. (No specimens.)

To all whom it may concern:

Be it known that I, THOMAS W. MILLER, a citizen of the United States, residing at Akron, in the county of Summit, State of Ohio, have 5 invented new and useful Improvements in Processes of Forming Hollow Seamless Rubber Articles, of which the following is a specification.

My invention relates to processes for making hollow flexible rubber articles—such as balls, punching-bags, water-bags, &c.—and has for its object to provide an improved process whereby a seamless article will be produced, the article being, moreover, cured on 15 the inside and being provided with an improved means for closing the necessary aperture therein. This object I accomplish in the manner and by the means hereinafter described and claimed, reference being had to 20 the accompanying drawings, in which—

Figure 1 is an elevation of a suitable form on which the article is given the desired configuration, the article being shown thereon in section. Fig. 2 is a sectional view of the 25 article after its removal from the form. Fig. 3 is a similar view of a completed article, in this instance a ball. Fig. 4 is a similar view of a completed water-bag.

Similar numerals of reference denote 30 corresponding parts in the several views.

In carrying out my improved process to form a rubber ball, for instance, I first provide a bath of rubber cement of the proper consistency, into which is dipped the solid 35 form 1, said dipping being repeated until there is formed thereon a ball 2 of the desired thickness. The form 1 is provided with an extension 3 not only for convenience in handling, but primarily for the purpose of forming 40 a neck or stem 4 on the ball 1 during the dipping, it being observed that said extension 3 is flared outward at 5 for a short distance from its point of juncture with the form to give the neck or stem 4 a similarly-flared configuration, as shown in Fig. 2. After the dipping has given the desired thickness to the ball, which may be thus made light or heavy, according to the use to which it is to be put, the rubber constituting the ball is then cured 45 while on the form and is then removed therefrom, which may be more readily accomplished by first heating the same by dipping it in hot

water and then distending the neck or stem 4 sufficiently to permit the passage therethrough of the form 1. The ball 2 (shown removed from the form in Fig. 2) is then turned inside out to bring the cured surface thereof on the inside, and the neck or stem 4 is reversed, so as to project into the ball, after which a plug 6, of rubber or other suitable 55 material, is inserted thereinto and firmly cemented to said neck or stem 4, as shown in Fig. 3, it being observed that said plug is of the exact configuration of said neck or stem, the inward-flaring shape of the two materially 60 aiding to prevent said plug being forced out, particularly if the ball is inflated. By forming this neck or stem 4 on the ball a firm opening is provided for the ball which neither bulges nor sinks when the ball is turned inside out, while the walls thereof afford a large 70 area for cementing thereto the plug 6.

I have shown in Fig. 4 an article 7 of a shape suitable for a water-bag, the same being made by the process hereinbefore described, the 75 plug 8 inserted thereinto being provided with a threaded aperture for the reception of a suitable stopper 9, usually employed in articles of this character, said plug 8 also having the usual flaring mouth 10 to provide for 80 pouring the water thereinto.

While I have shown only a solid plug and a threaded plug, it will be understood that any other form of plug—a valved plug for inflation, for instance—may be employed, the 85 form of plug depending entirely on the nature and use of the article.

Having thus described my invention, what I claim as new, and desire to secure by Letters Patent, is—

1. The process of manufacturing seamless hollow rubber articles, which consists in first forming a body portion and a neck or stem by dipping a suitable form in a bath of rubber, then stripping said article so formed from 95 said form, then turning said neck or stem within the interior of the body portion, and finally inserting a suitable closing-plug in said neck or stem, substantially as set forth.

2. The process of manufacturing seamless hollow rubber articles, which consists in first forming a body portion and a neck or stem by dipping a suitable form in a bath of rubber, then curing said article so formed while

on the form, then stripping said article from the form, then turning said article inside out to bring the cured surface on the inside, then turning said neck or stem within the interior 5 of the body portion, and finally inserting and fastening a suitable closing-plug in said neck or stem, substantially as set forth.

In testimony whereof I have hereunto set my hand in the presence of two subscribing witnesses.

THOMAS W. MILLER.
